UNITED STATES PATENT OFFICE

2,661,995

FILLER STRUCTURE FOR KITCHEN CABINETS

Harvey G. Knuth, Elgin, Ill., assignor to Lyon Metal Products, Incorporated, Aurora, Ill., a corporation of Illinois

Original application February 23, 1945, Serial No. 579,457. Divided and this application August 15, 1949, Serial No. 110,875

4 Claims. (Cl. 312—111)

1

This invention relates to filler structures for kitchen cabinet constructions.

The present application is a division of my application Serial No. 579,457, filed February 23, 1945.

An object of the invention resides in providing a kitchen cabinet which may be built up of two or more juxtaposed basal cabinet sections and separately completed top sections assemblable end to end, and wherein an end scribe plate may be utilized to cover a void between adjacent cabinet walls where the space is not an exact multiple of the width of the particular cabinets used for the installation.

Other and further objects of the invention will be apparent from a perusal of the following specification when taken in connection with the accompanying drawings, wherein:

Figure 1 is a perspective view showing the use of a filler;

Figure 2 is a perspective view of the filler members; and

Figure 3 is a section taken on the line 3—3 of Figure 1.

The present invention permits the factory production and installation of standard cabinet sections to provide a finished cabinet installation of any desired width and length and provides a filler structure whereby hideous joints, which collect moisture and dirt between sections, are eliminated.

Fig. 1 discloses a cabinet installation where in return lines of cabinets forming a U-shaped arrangement, the two confronting cabinets 124 do not contact. That is, there is a space left between the two and it thereupon becomes necessary to fill in this space by the construction shown in Figs. 2 and 3.

In this type of cabinet I utilize the scribe plates 130 and 131 shown in Figure 2 which include the basal foot portion 133 corresponding to the basal portion of the cabinet and having the upstanding right angled flanges 134 and 136 of desired length. This foot 133 has a basal rearwardly extending flange 133a and likewise has a vertical laterally extending flange 133b for rigidity. Supported by, mounted on, and preferably formed integrally with the wall 123 is a horizontal overhanging wall 133c, the forward end of which extends at right angles upwardly to provide a front vertical flange 136 which may be cut vertically as along the line 136' to desired width, thus forming the free edge 137. This cut will also be formed through the foot portion 133. The flange 136 has an integral flange

2

134 of desired length bent at right angles thereto and lies preferably in the plane of the basal lateral flange 133b. The width of the overhang 133c and its flange 136 is preferably cut similarly to the width of the foot 133 taken in a horizontal direction as viewed in Figure 2. Flange 134 is provided with vertically spaced fastener receiving holes 137' whereby the flange 134 may be united by fasteners 137" to the adjacent side wall of cabinet 124. This construction is illustrated particularly in Figure 3 wherein the scribe plate 130 adjustably cooperates with the spaced flanges 140 and 142 of the scribe plate 131. The flanges 140 and 142 of the scribe plate 131 are sufficiently spaced apart and are constructed by welding a right angled piece 143 as at 144 so that the flange 136 of the scribe plate 130 will slide relatively thereto to adjust the spacing between the two cabinets or between a wall and a cabinet, as shown in the parent application, Serial No. 579,457. As shown in Figures 2 and 3, the single flange of the scribe plate 131 is provided with vertically spaced fastener openings 131a to receive fasteners 131b to connect said plate to the adjacent side wall of the spaced cabinet 124, see Figure 2. In the construction shown in Figures 2 and 3 the flange 136 is in general cut down to fit the space to be filled and then the cut edge will be positioned between the opposed flanges 140 and 142. The ends of the flanges 140 and 142 are preferably given a finish, whereas the free edge 137 may be left unfinished. In both of these uses of these filler parts, an elongated top is preferably selected or cut which will extend across and cover both of the adjacent cabinets, as disclosed in said parent application.

When the filler pieces are to be used to cover the distance between the cabinet 124 and the room wall as shown in the parent application, the angular filler piece 130 has its flange 134 merely abutting the wall.

Obviously the invention is not limited to the specific details of construction disclosed herein but is capable of other modifications and changes without departing from the spirit and scope of the appended claims.

Having thus described my invention, what I claim as new and desire to secure by Letters Patent is:

1. Interfitting scribe plates comprising a first scribe plate having a vertical basal wall and a horizontal forwardly extending overhanging wall terminating forwardly in an upwardly extending vertical front flange lying parallel to

said vertical basal wall, said vertical flange having a laterally, normally extending integral flange formed with vertically spaced openings, said horizontal overhanging flange being of less width than the width of said basal vertical wall, and a second scribe plate of substantially the length as said upwardly extending vertical flange of said first scribe plate, said second scribe plate having a first flange formed with spaced, vertically extending fastener openings, and a 10 pair of spaced, parallel, relatively short flanges extending normally from the front vertical edge of said first flange to receive slidingly the vertical front flange of said first scribe plate.

2. A filler structure for filling gaps between 15 spaced apart wall portions in cabinet installations comprising a first scribe plate having a vertical basal wall and a horizontal forwardly extending overhanging wall, an upwardly extending vertical front flange formed on the forward edge of said overhanging wall and lying parallel to said vertical basal wall, and a second scribe plate of substantially the length of said upwardly extending vertical flange of said first scribe plate, said second scribe plate having a 25 pair of spaced parallel relatively short flanges extending in a direction parallel to the vertical flange of said first scribe plate to receive slidingly the vertical front flange of said first scribe plate.

3. A filler structure as set forth in claim 2 wherein the horizontal overhanging wall has a width less than the width of the vertical basal wall.

5. 4. A filler structure as set forth in claim 2, wherein the vertical front flange of the first scribe plate has a laterally and normally extending flange formed on one edge thereof with vertically spaced openings, and the second scribe plate has a flange disposed perpendicularly to the pair of short flanges and provided with spaced vertically extending fastener openings.

HARVEY G. KNUTH.
